(57) **CLAIM**

The ornamental design for an implantable apheresis port, as shown and described.

DESCRIPTION

FIG. 1 is a rear perspective view of an implantable apheresis port;

FIG. 2 is a front perspective view of the implantable apheresis port illustrated in FIG. 1;

FIG. 3 is a top view of the implantable apheresis port illustrated in FIG. 1;

FIG. 4 is a bottom view of the implantable apheresis port illustrated in FIG. 1;

FIG. 5 is a first side view of the implantable apheresis port illustrated in FIG. 1;

FIG. 6 is a second side view of the implantable apheresis port illustrated in FIG. 1;

FIG. 7 is a rear view of the implantable apheresis port illustrated in FIG. 1; and,

FIG. 8 is a front view of the implantable apheresis port illustrated in FIG. 1.

The broken lines immediately adjacent the shaded areas represent the bounds of the claimed design while all other broken lines are directed to environment; the broken lines form no part of the claimed design.
